UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

COATING APPARATUS.

1,315,948.

Specification of Letters Patent. Patented Sept. 16, 1919.

Application filed March 15, 1918. Serial No. 222,602.

To all whom it may concern:

Be it known that I, JOHN W. COSGROVE, a citizen of the United States, residing at Medford, in the county of Middlesex and 5 State of Massachusetts, have invented certain Improvements in Coating Apparatus, of which the following description, in connection with the accompanying drawings, is a specification, like reference characters on 10 the drawings indicating like parts in the several figures.

My invention relates to coating apparatus and more particularly to that type in 15 which coating material is applied simultaneously to both sides of the work, though not necessarily confined to such organizations.

An object of the invention is to provide 20 improved means for yieldably supporting an applying member and for supplying the coating material thereto. For this purpose I prefer to mount the receptacle for the coating material pivotally, the applying member being movable upon the receptacle in 25 its coating action and yielding by virtue of the movement of the receptacle about its fulcrum. To obtain the desired holding capacity for the coating material, the receptacle may have, in addition to the ful- 30 crum portion and applying portion, a reservoir portion extending at one side of the fulcrum; and, because of the depth of the receptacle, I have shown a movable feed member for supplying the coating material 35 to the applying member and driven therefrom.

Another object of the invention is to 40 render a feed member, as above mentioned, particularly when it is in the form of a roll, effective in supplying the coating material. To this end, the roll is toothed and the faces of the teeth are so designed as best to lift the material from its receptacle and deliver it to the applying member.

45 With rotatable applying members, and especially those receiving coating material from an elevated receptacle, there is a tendency to carry the material along coöperating frame or abutment elements, upon which 50 it accumulates and drips upon the work or its support. One of the objects of my invention is to avoid this by furnishing means for preventing the passage of the coating

material to the point of accumulation. One means for attaining this object is to form 55 a groove in the abutment along the periphery of the applying member.

One of the numerous forms which my invention may assume is illustrated in the accompanying drawings, in which— 60

Figure 1 is a top plan view of the lower tank structure of one embodiment of the invention;

Fig. 2 is a side elevation of the machine, parts being broken away and in section; 65

Fig. 3 is a partial end elevation looking from the left in Fig. 2;

Fig. 4 is a detail in perspective of the upper applying roll, with its abutment plates and slides; and 70

Fig. 5 is a detail in elevation of the inside of one of the abutment plates.

The frame of the machine is shown as 75 consisting of a base portion 10, suitable for mounting upon a bench and having a horizontal arm 12 in which is journaled a shaft 14 rotated through power applied to fast and loose pulleys 16. Fixed upon the shaft, between separated extensions 18, 18 of the frame arm, is a suitable applying roll 20 80 which receives the coating material, as cement, from a tank 22 carried upon a horizontal surface at the upper side of the arm 12. The passage of the cement from the tank to the roll is controlled by a valve 24. 85 From the valve the flow is directed to the roll by vertical inner and outer abutment plates 26, 26 and by horizontal slides 28 and 30. The abutment plates are located one at the inner side of the roll, between it and 90 a vertical face upon the end of the frame arm 12, while the other plate is forced against the outer surface of the roll by screws 32 threaded through a bar 34 secured to the ends of the extensions 18. The slides 95 28 and 30 have their outer extremities in slots in the upper portions of the extensions 18, their upper surfaces being below the tops of the extensions. At their inner ends they extend into proximity with the 100 periphery of the roll 20. They are secured in place by screws 36 threaded into the frame extensions through slots which are recessed to receive the heads of the screws. By these slotted connections the slides may 105 be adjusted with reference to the roll, and,

since the screws 36 are beneath the tank, the slides can only be varied in position when the tank is removed. This prevents unskillful operators from tampering with the adjustment, which may best be made, according to the grade of cement which is to be used, by an experienced person when the filled tank is put in place. The slide 28 which is at the down-going side of the roll 10 controls the amount of cement which is carried from the tank by the applying surface to the work, while the opposite slide 30 bars the passage of cement from the tank in this direction yet allows any excess brought up 15 from the work to be carried by it to join the fresh supply from the tank.

As thus far described, the apparatus is generally as disclosed in my Patent No. 1,242,925, dated October 16, 1917. It is found that as the roll 20 rotates in the direction of the arrow in Fig. 5, the cement is not only carried by the peripheral applying surface beneath the slide 28, but also tends to creep between the sides of the roll 25 and the adjacent faces of the abutment plates 26 and gather at α where the periphery of the roll emerges from between the plates and there accumulates to drip and deface the work. This I avoid by spacing the edges of the roll and the abutments from one another at these points, preferably by a groove or recess 38, which is formed in each abutment extending from α , where the edges of the roll leave the abutment in its 35 rotation, nearly to the top of said abutment. Except at the narrow spaces between the ends of the slots and the bottom of the tank, this arrangement eliminates the contacting surfaces along which the creeping of cement 40 occurs. The slight accumulation at the inner extremities of the slots hardens and does not reach the dripping points at α . If necessary, the slots may be occasionally cleaned by the introduction of a pointed 45 implement.

The base portion 10 of the frame is divided and through this space beneath the frame arm 12, extends a lower tank member, the tank preferably consisting of an integral 50 structure including a fulcrum arm 40, a gear chamber 42, an applying portion 44, and a reservoir 46. The arm 40 is pivoted at 48 near the inner end of the frame arm 12, and in bearings adjacent to the pivot 55 and at the opposite end between the gear chamber and the applying portion is journalized a horizontal shaft 50 having fixed at its outer extremity, beneath and in vertical alinement with the roll 20, an applying 60 roll 52. The shaft 50, with its roll 52, is rotated from the shaft 14 through gearing 54 which is located adjacent to the fulcrum 48. This permits the tank structure to swing about its pivotal point without interference with the driving engagement of the 65

gearing 54. To hold the lower tank normally upward so that the rolls 52 and 20 may be in co-operation, it is provided with a depending arm 56 engaged by the inner end of a helical spring 58 surrounding a guide 70 rod 60 pivoted near the lower end of the arm 56 and resting, at its outer extremity against a screw 62, which has an opening to receive the rod 60. The screw 62 is threaded into a boss in the frame and by its adjustment enables the force with which the roll 52 is pressed up toward the roll 20 to be varied. A stop screw 63 threaded through the frame opposite the screw 62 and contacting with the arm 56 adjustably limits the 75 upward movement of the roll 52. To give the proper capacity for containing cement, the bottom of the applying portion 44 is considerably below the lower edge of the roll 52, and to this applying portion is connected 80 the reservoir portion 46 of the tank, which extends to one side of the frame and has an inclined bottom wall causing the contents to drain toward the applying portion of the tank so that all the cement may be used. 85 Access may be had to the reservoir through an opening at its outer and upper portion, normally closed by a horizontal cover plate 64 secured in place by thumb screws 66. The top of the reservoir does not exceed in 90 height the upper edge of the applying portion where the lower roll 52 leaves it, so that the level of cement in the tank can not rise high enough to overflow at the opening for the roll. 100

The depth of the lower tank is such that an applying roll of the desired diameter can not operate in contact with the cement when it is low. For this reason cement is supplied to the roll 52 by a feed roll 68 fixed upon a 105 shaft 70, which extends through the chamber 42 and applying portion 44 of the tank, having a bearing in the intermediate wall 71. The shaft 70 is rotated from the shaft 50 through gearing 72 located within the 110 chamber 42 and including an intermediate idler gear fast upon a shaft 74 journaled in the tank walls. Lubricating openings 76 for the shaft 50, 70 and 74 may be provided in the wall 71. Access to the chamber 42 may 115 be had through an opening closed by a cover plate 78 secured in place by screws. A removable plate 80 normally closes an opening in the outer end of the tank, allowing the rolls 52 and 68 to be reached and the cement 120 cleaned from the receptacle. The feed roll 68 is toothed, each tooth having a peripheral end surface 82 which may be arcuate and which moves just out of contact with the applying surface of the roll 52. The forward surface 84 of each tooth is preferably substantially radial, the rear surface 86 being inclined from the flattened or curved end toward the base of the succeeding tooth, into which it preferably merges by a curved 125 130

depression 88. As the feed wheel is rotated in the direction of the arrow in Fig. 3, each tooth, as it emerges from the cement, by its forward radial face effectively lifts a charge.

- 5 This, because of the inclination of the directing surface 86 and the centrifugal force generated in the revolution of the teeth, as it advances rounds out over the peripheral surface 82, which thus delivers it to the applying roll. An unduly heavy supply is avoided by a separation of the surfaces 82 from the applying surface. If any excess of cement is received by the roll 52, it is removed by a scraper 90, which is adjustably secured at the top and outer side of the applying portion 44 of the lower tank by a screw 92 extending through a slot.

As the work enters between the rolls 20 and 52, the lower tank, by its pivotal movement under the influence of the spring 58, holds the applying rolls and work in proper contact and permits yield for inequalities in the work. Since this tank is a self-contained structure carrying the entire supply 25 of cement and the movable applying elements, no difficulty is encountered through leakage as a result of the yield of the lower applying roll.

- The width of the band of cement applied 30 to the work by the rolls 20 and 52 is determined by a gage 94 carried upon the top of the tank above the wall 71. The vertical face of this gage is adjacent to the rolls and with it the work contacts. The upper 35 surface of this gage forms, with the inner end of the roll 20, a converging throat (see Fig. 3), into which, in absence of means for preventing it, the operator might insert the work, causing its forward edge to be cut between the rotating roll and the gage. This is avoided by a guard, shown as in the form 40 of a rod 96 projecting horizontally from the upper portion of the gaging surface and in proximity to the periphery of the roll 20. As the operator feeds the work over the forward upper surface of the lower tank, the rod 96 prevents said work from being so raised that it can be caught between the upper roll and gage and insures its delivery 45 between the rolls.

Having thus described my invention, what I claim as new and desire to secure by Letters Patent of the United States is:—

1. In a coating apparatus, a frame, a work-engaging element carried thereby, a receptacle for coating material pivotally mounted upon the frame and extending into proximity with the work-engaging element, and a rotatable applying member journaled 55 within the receptacle and being movable therewith toward and from the work-engaging element.

2. In a coating apparatus, a frame, a rotatable applying roll carried thereby, a receptacle for coating material pivoted upon

the frame at one side of the applying roll and extending beneath it, and an applying roll journaled in the receptacle for coöperation with the first-named roll.

3. In a coating apparatus, a frame, a rotatable applying roll carried thereby, a receptacle for coating material pivoted upon the frame at one side of the applying roll and extending beneath it, an applying roll journaled in the receptacle for coöperation 70 with the first-named roll, and a supply roll for the applying roll journaled in the receptacle. 75

4. In a coating apparatus, a frame, a rotatable applying roll carried thereby, a receptacle for coating material pivoted upon the frame at one side of the applying roll and extending beneath it, and an applying roll journaled in the receptacle for coöperation with the first-named roll, the bottom 80 of the receptacle being inclined downwardly to a point under the lower applying roll.

5. In a coating apparatus, a frame, a coating roll, and a receptacle having as an integral structure a fulcrum portion for 85 pivotally connecting it to the frame and a bearing portion for movably supporting the roll in the receptacle.

6. In a coating apparatus, a frame, a coating roll, and a receptacle having as an 90 integral structure a fulcrum portion for pivotally connecting it to the frame, a bearing portion for movably supporting the roll in the receptacle and a reservoir portion extending at one side of the frame. 95

7. In a coating apparatus, a frame, a coating roll, a receptacle having as an integral structure a bearing portion for rotatably supporting the roll within the receptacle, an arm by which the receptacle is 100 pivotally mounted upon the frame and a second arm, and yieldable connections between the second arm and the frame. 105

8. In a coating apparatus, a frame, a receptacle pivotally mounted upon and projecting from the frame, the height of said reservoir not exceeding that of the receptacle, the receptacle having a reservoir extending from it at one side of the frame, and a coating member carried by the receptacle. 110

9. In a coating apparatus, a frame, a receptacle having an arm by which it is fulcrumed to the frame and a reservoir projecting from the receptacle beside the arm to a height not exceeding that of the receptacle, and a coating member mounted on the receptacle. 120

10. In a coating apparatus, a frame, a driving shaft journaled therein, a receptacle pivoted on the frame, a shaft journaled in the receptacle, gearing connecting the shafts adjacent to the pivotal point of the receptacle, and an applying roll carried by the receptacle shaft. 125

11. In a coating apparatus, a frame, a

driving shaft journaled therein, a receptacle pivoted on the frame, a shaft journaled in the receptacle, gearing connecting the shafts adjacent to the pivotal point of the receptacle, an applying roll carried by the receptacle shaft, and a feed roll rotatable in the receptacle and coöperating with the applying roll.

12. In a coating apparatus, a frame, a driving shaft journaled therein, a receptacle pivoted on the frame, a shaft journaled in the receptacle, gearing connecting the shafts adjacent to the pivotal point of the receptacle, an applying roll carried by the receptacle shaft, a feed roll rotatable in the receptacle and coöperating with the applying roll, and gearing journaled in the receptacle and connecting the applying and feed rolls.

20 13. In a coating apparatus, a receptacle for coating material, applying and feed rolls journaled in the receptacle, and gearing for the rolls, there being a chamber formed in the receptacle for inclosing the 25 gearing.

14. In a coating apparatus, a frame, a receptacle for coating material provided with an arm fulcrumed upon the frame, applying and feed rolls journaled near one side of the 30 receptacle in a portion for containing the coating material, and gearing connecting the rolls, there being a chamber formed in the receptacle between the arm and material-containing portion and inclosing the 35 gearing.

15. In a coating apparatus, a rotatable applying roll, and a rotatable toothed feed roll coöperating therewith, the teeth of the feed roll having their forward faces substantially radial and their opposite faces inclined rearwardly from the outer end toward the bases of the succeeding teeth.

16. In a coating apparatus, a rotatable applying roll, and a rotatable toothed feed 45 roll coöperating therewith, the teeth of the feed roll having their forward faces substantially radial and meeting at their outer ends peripheral faces, from which are faces inclined rearwardly toward the radial faces 50 of the succeeding teeth.

17. In a coating apparatus, a tank, an applying roll rotatable in the tank, and a toothed feed roll rotatable in the coating material at the lower portion of the tank 55 beneath the applying roll, the ends of the teeth of the feed roll being in proximity to but out of contact with the applying roll, each tooth being provided with a substantially radial face and an opposite face inclined toward the radial faces of the succeeding teeth.

18. In a coating apparatus, a tank and applying roll rotatable in the tank, and a toothed feed roll rotatable in the coating 65 material at the lower portion of the tank be-

neath the applying roll, the teeth having at their outer extremities supply surfaces for the applying roll and being provided with forward lifting faces and rear directing faces.

70

19. In a coating apparatus, a tank for coating material, an applying roll receiving material from the tank, and an abutment into proximity with which the end of the roll extends, there being means between the 75 roll and abutment for preventing the passage of coating material.

20. In a coating apparatus, a tank for coating material, an applying roll receiving material from the tank, and an abutment 80 into proximity with which the end of the roll extends, there being means between the roll and abutment and extending along the periphery of the roll for preventing the passage of coating material.

85

21. In a coating apparatus, a tank for coating material, a rotatable applying roll receiving material from the tank, and an abutment into proximity with which the end of the roll extends, the abutment and 90 periphery of the roll being spaced from one another where the periphery in its rotation leaves the abutment.

22. In a coating apparatus, a tank for coating material, a rotatable applying roll 95 receiving material from the tank, and an abutment into proximity with which the end of the roll extends, the abutment being provided with a recess along the periphery of the roll with an opening where the periphery in its rotation leaves the abutment.

100

23. In a coating apparatus, a tank for coating material, an applying member rotatably mounted at the bottom of the tank and receiving the coating material upon its 105 applying surface, and plates contacting with the ends of the roll, said plates having grooves along the periphery of the roll.

105

24. In a coating apparatus, a tank for coating material, an applying member rotatably mounted at the bottom of the tank and receiving the coating material upon its applying surface, and plates for guarding against the flow of material from the tank along the ends of the roll, said plates including grooves extending from points near the bottom of the tank through the edges of the plates.

110

25. In a cementing apparatus, a rotary applying member and a relatively stationary member having converging edges, and a member for contact with the work arranged to prevent the entrance of said work between the converging edges.

115

26. In a cementing apparatus, a rotary applying member, a work gage, and a guard member situated adjacent to the applying member and gage for contact with the work.

120

27. In a cementing apparatus, an applying roll, a gage having a surface for con- 125

130

tact with the work, and a guard projecting from the work-engaging surface of the gage adjacent to the periphery of the applying roll.

5 28. In a cementing apparatus, an applying roll, a gage having a surface for contact with the work and a surface which with

the periphery of the roll forms a converging throat, and a guard rod projecting from the work-engaging surface of the gage adjacent to said throat.

In testimony whereof I have signed my name to this specification.

JOHN W. COSGROVE.
